TRAFFIC SIGNAL

Robert O. Ferguson, Bristol, Tenn., assignor of
one-half to Bristol Steel & Iron Works, Inc.,
Bristol, Va., a corporation of Virginia

Application July 26, 1949, Serial No. 4,147

Term of patent 14 years

(Cl. D72—1)

To all whom it may concern:

Be it known that I, Robert O. Ferguson, a citizen of the United States and a resident of Bristol, in the county of Sullivan and State of Tennessee, have invented a new, original, and ornamental Design for a Traffic Signal, of which the following is a specification, reference being had to the accompanying drawing, forming part thereof.

The single drawing figure is a front perspective view of a traffic signal showing my new design.

The dominant features of my design reside in the portions shown in full lines, and in particular, the front face of the signal design. The back thereof is conventional.

I claim:
The ornamental design for a traffic signal, as shown and described.

ROBERT O. FERGUSON.
